Primary Examiner — John Windmuller*Assistant Examiner* — Luqman McNeil(74) *Attorney, Agent, or Firm* — Rabin & Berdo, P.C.(57) **CLAIM**

The ornamental design for a heat pad, as shown and described.

DESCRIPTION

FIG. 1 is a perspective view of an embodiment of a heat pad showing our new design;

FIG. 2 is a front elevation view thereof;

FIG. 3 is a rear elevation view thereof;

FIG. 4 is a front elevation view thereof showing a first mode in use; and,

FIG. 5 is a front elevation view thereof showing a second mode in use.

The broken line environmental showing is for illustrative purposes only and does not form part of the claimed design.

1 Claim, 3 Drawing Sheets(56)
